(57) **CLAIM**

The ornamental design for a dual durometer cleat, as shown and described.

DESCRIPTION

FIG. 1 is a top plan view of a dual durometer cleat showing my new design; and,

FIG. 2 is an offset rear view of the cleat, the broken line showing for illustrative purposes only and forms no part of the claimed design.

The broken line in FIG. 2 encloses structure that forms no part of the claimed design and is shown for illustrative purposes only.
